Hawson & Hawson

UNITED STATES PATENT OFFICE

JOSEPH KEMME, OF PHILADELPHIA, PENNSYLVANIA, ASSIGNOR TO CHARLES R. NALLE, OF PHILADELPHIA, PENNSYLVANIA

CASTER

Application filed August 16, 1930. Serial No. 475,775.

This invention relates to the general class of devices known as casters which are generally used for supporting articles of furniture, or the like, and has for its general object the provision of a device of the class indicated which shall be simple in construction and efficient in operation to produce the desired results.

The invention has as a further object the provision of a device of the class indicated which embodies therein various improved features which result in a product of improved construction and capable of results heretofore unattained.

A further and more specific object of the invention is to provide a device of the class described which may be adjusted to vary the height of the article supported above the floor, and is particularly useful when applied to the legs of tables or other articles of furniture. When a plurality of devices according to my invention are applied to such an article of furniture, each may be individually adjusted so that each caster has an equal bearing on the floor.

A still further object of the invention is to provide a device of the type mentioned which may be easily adjusted and which will not get out of adjustment.

Another object of the invention is to provide a caster which will rigidly support any article to which it is attached, and which article will have no tendency to wobble.

These and other objects of the device according to my invention will be obvious to those skilled in the art from the following detailed description in connection with the accompanying drawings.

In the drawings:

Fig. 1 shows a side elevation of the preferred embodiment of my improved caster;

Fig. 2 is a sectional view of the preferred embodiment of my device;

Fig. 3 is a perspective view of the guide-retaining member of the device of Figs. 1 and 2;

Fig. 4 shows in perspective the nut-enclosing yoke of the device of Figs. 1 and 2;

Figs. 5 and 6 are perspective views, respec-

tively, of the recessed adjusting nut and its associated washer;

Fig. 7 is a side elevation of a modified form of my improved caster;

Fig. 8 is a sectional view of the device of Fig. 7;

Fig. 9 is a perspective view of the guide-retaining member of the modified form of my device;

Fig. 10 is a perspective view of the nut-enclosing yoke of the modified form; and

Figs. 11 and 12 show in perspective the recessed nut and its associated washer used in the modified form and which are similar to the corresponding elements of the preferred embodiment.

Referring to Figs. 1 and 2 of the drawings, there is shown a caster having the usual roller 1 rotatable about an axle 2 which is supported by bracket member 3. This bracket member has depending arms 4 which support the roller axles at their extremities. This structure is, of course, the usual structure of the lower portion of an ordinary caster. A shank 5 has its lower end 6 of small diameter and is supported in an upright position on the bracket member. The shank extends through an opening in the bracket member and is held firmly by means of washers 7 and 8 and riveted portion 9. The middle section of shank 5 is threaded as at 10, while the upper end is unthreaded. A knurled adjusting nut 12, shown more clearly in Fig. 5, threadedly engages the middle or threaded portion of the shank.

This nut is provided with a recess 13 in its upper surface, which is adapted to receive a spring washer 14, shown more clearly in Fig. 6, which may take the form of an ordinary lock washer.

A yoke 15, which is clearly shown in Fig. 4, has its main body portion partly enclosing the adjusting nut and is provided with extending wing portions 16 and 17 having, respectively, sets of threaded apertures 18 and 19. The upper and lower faces of the yoke are provided with elongated slots 20. The threaded portion 10 of shank 5 has diametrically opposite flattened portions, as shown, so that this portion of the shank coincides in

cross section with the elongated slots 20 of the yoke. This construction prevents the shank from turning with respect to the yoke. A guide-retaining member 23, shown more clearly in Fig. 3, is provided with extending wing portions 24 and 25 similar to those of the yoke. Member 23 also has a centrally located opening 28 with its peripheral portion raised. Sets of holes 26 and 27 are provided respectively in wing portions 24 and 25. These wing portions are adapted to coincide with the wing portions of yoke 15, and screws 21 and 22 pass through holes 26 and 27 to threadedly engage holes 18 and 19. This firmly attaches the guide-retaining member to the yoke.

A guide 30 is provided having its inside diameter of such dimension that the unthreaded portion 11 of shank 5 fits snugly therein. The guide is provided with integrally extending flanges 31 and 32, the latter being preferably formed by simply bending out the lower end of the guide. The guide is firmly held by means of the retaining member 23 by having its lower flange 32 secured under the upturned portion of the retaining member, as shown more clearly in Fig. 2. A supporting member 33 having serrations 34 is supported on the guide between flange 31 and the upstanding portion of the retaining member 23.

In assembling the above-described device, it is necessary, before riveting the shank to the roller support, to thread the adjusting nut with its associated spring washer and enclosing yoke upon the threaded portion of the shank. The shank is then attached to the roller support. The supporting member 33 and retaining member 23 are placed over the end of guide 30 and the lower extremity of the guide is then bent outward to form flange 32. This assembled structure is then mounted on the supporting yoke by means of the attaching screws. In this form of my device, it will be noted that adjusting nut 12 may be raised or lowered to raise or lower the supporting member 33, which is adapted to support the leg of an article of furniture or the like. The serrations, of course, bite into the leg in the usual manner. In this way, the height of the lower extremity of the leg or article supported above the floor may be varied. After the adjustment of the device has been made, any turning of the device will not cause turning of the shank with respect to the adjusting nut, or vice versa, because the spring washer forms a binding connection between the adjusting nut and the yoke and the latter is unable to turn relative to the shank because of its slotted openings and the corresponding flattening of the threaded portion of the shank.

The swiveling action of the device takes place between the guide and the guide-retaining member. In other words, when the

shank turns it carries with it the guide-retaining member, while guide 30 and supporting member 33 are stationary. The guide-retaining member is rotatable about flange 32 of the guide. Obviously, this assembly provides a device which will not get out of adjustment due to movement of the supported article, and when the adjusting nut has once been positioned, the only action which can occur thereafter is the desired swiveling action. The frictional connection between the yoke and the adjusting nut formed by the spring washer prevents any displacement of the latter along the shank due to turning of the shank.

In Figs. 7 and 8, I have shown a modified form of my device. In these figures, the usual roller-supporting structure comprising a roller 1 supported by axle 2 which, in turn, is supported by member 3 is again provided. The upstanding shank 5 is attached to the roller-supporting member in the same manner as before, utilizing a pair of washers 7 and 8 and riveted portion 9. In this instance, however, the shank 5 is threaded throughout its entire upper portion, and the diametrically opposite flattened portions extend the entire length of the threads. A recessed adjusting nut 12 with an associated spring washer 14 are again provided and the nut threadedly engages the shank. The nut-enclosing yoke 15a, having a different form than that described above, is provided and has elongated slots 20 in its upper and lower surfaces to accommodate the flattened threaded shank as previously described. A guide-retaining member 23a is provided with a centrally located aperture 28 having an upstanding peripheral portion 29 as before. This member, however, is provided with clamping portions 35 and 36 which are adapted to embrace the upper portion 37 of yoke 15a. A guide member 30 is again provided which carries a serrated supporting member 33 and has its end portion bent outward to provide a flange 32 as described above.

In assembling this modified form of my device, it is not necessary to place the adjusting nut and its yoke upon the shank before attaching the latter to the roller support. In this instance, the shank may be first attached to the roller support. The remainder of the structure may be assembled separately. The supporting member 33 and retaining member 23a are first placed over the end of the guide, and the lower extremity of the guide is bent outward to form flange 32. The retaining member is then placed on the yoke and its depending sides are bent to form clamping portions 35 and 36 which embrace the yoke. The spring washer is next placed in its recess. The yoke and the assembly supported by it is then placed in cooperative relation with the adjusting

nut and the latter is threadedly placed upon the shank. It will be noted that in this modified form of my device, the shank is also prevented from turning relative to the adjusting nut and the structure supported thereby due to the flattened threads of the shank and the elongated openings in the yoke. In this instance, the spring washer also forms a binding connection between the adjusting nut and the yoke so that the nut will not turn relative to the yoke of its own accord. Since the yoke cannot turn, the nut is prevented from turning also.

While in this modified form of my device, I have provided the shank with threads throughout its upper portion, which enables the assembly of the supporting structure after the shank is mounted, it will be obvious that I may in this case also have the upper portion of the shank unthreaded as in the preferred embodiment. In such case, however, it would be necessary as before to mount the adjusting nut and the structure supported thereby on the shank before attaching the latter to the roller support, since the adjusting nut could not be placed over the unthreaded portion of the shank. In the modified form of my device, the entire swiveling action is the same as in the preferred embodiment of Figs. 1 and 2.

From the above disclosure, it will be apparent that I have provided a caster of improved construction having features which add greatly to the efficiency of the device. Obviously, various changes in the details of construction of my device may be made without departing from the spirit or scope of the invention. Therefore, the above disclosure is to be understood as serving the purpose of illustration only and not as limiting my invention. The invention is to be limited only by the scope of the appended claims.

I claim:

1. A device of the class described having a threaded upstanding shank, a guide slidably and rotatably receiving said shank, a weight supporting nut threaded adjustably on said shank under said guide, and a yoke surrounding said nut and supporting said guide.

2. A device of the class described having a threaded upstanding shank, a guide slidably and rotatably receiving said shank, a weight supporting recessed nut threaded adjustably on said shank, a spring washer in said recess, and a yoke surrounding said nut and washer and supporting said guide.

3. A device of the class described having a threaded upstanding shank with its threaded portion flattened on opposite sides, a guide slidably and rotatably receiving said shank, a weight-supporting nut threaded adjustably on said shank under said guide, and a yoke having elongated openings for receiving said flattened threaded portion of said shank surrounding said nut and supporting said guide.

4. A device of the class described having a threaded upstanding shank, a guide slidably and rotatably receiving said shank, a weight-supporting nut threaded adjustably on said shank under said guide, a yoke surrounding said nut, and a retaining member for said guide carried by said yoke. 70

5. A device of the class described having a threaded upstanding shank, a guide slidably and rotatably receiving said shank, a weight-supporting nut threaded adjustably on said shank under said guide, a yoke surrounding said nut, and a retaining member for said guide removably attached to said yoke. 75

6. A device of the class described having a threaded upstanding shank, a guide slidably and rotatably receiving said shank, a weight-supporting nut threaded adjustably on said shank under said guide, a yoke surrounding said nut, and a retaining member 85 for said guide having clamping portions embracing said yoke.

7. A device of the class described having a threaded upstanding shank, a guide slidably and rotatably receiving said shank and 90 having a flange at one end, a weight-supporting nut threaded adjustably on said shank under said guide, a yoke surrounding said nut, and a retaining member for said guide carried by said yoke, a portion of said member 95 rotatably retaining the flange of said guide.

8. A device of the class described having a threaded upstanding shank, a guide slidably and rotatably receiving said shank and 100 having a pair of spaced flanges, a weight-supporting nut threaded adjustably on said shank under said guide, a yoke surrounding said nut, a retaining member for said guide carried by said yoke, a portion of said member 105 rotatably retaining one flange of said guide, and a serrated supporting member on said guide between said portion and the other flange of said guide.

9. In a device of the class described, an 110 upstanding shank having its lower portion threaded, a guide slidably and rotatably receiving said shank and closely surrounding the upper unthreaded portion of said shank to prevent wobble of said shank in said guide, 115 and a weight-supporting nut threaded adjustably on said shank and supporting said guide.
